UNITED STATES PATENT OFFICE.

JOHN BOE, OF BATEMAN, SASKATCHEWAN, CANADA.

DESIGN FOR A TOY.

47,988.

Specification for Design.

Patented Oct. 19, 1915.

Application filed March 30, 1915. Serial No. 18,204. Term of patent 7 years.

To all whom it may concern:

Be it known that I, JOHN BOE, a subject of the King of Great Britain, residing at Bateman, in the Province of Saskatchewan, Dominion of Canada, have invented a new, original, and ornamental Design for Toys, of which the following is a specification, reference being had to the accompanying drawing, forming part thereof.

I claim:

The ornamental design for a toy, as shown.

JOHN BOE.
